(57) CLAIM

The ornamental design for a patient interface device, as shown and described.

DESCRIPTION

FIG. 1 is a front perspective view of an embodiment of a patient interface device according to our new design; FIG. 2 is a rear perspective view of the patient interface device shown in FIG. 1; FIG. 3 is a front elevational view of the patient interface device shown in FIG. 1; FIG. 4 is a rear elevational view of the patient interface device shown in FIG. 1; FIG. 5 is a right side elevational view of the patient interface device shown in FIG. 1, the left side elevational view being similar thereto; FIG. 6 is a top plan view of the patient interface device shown in FIG. 1; FIG. 7 is a bottom plan view of the patient interface device shown in FIG. 1; FIG. 8 is a front perspective view of another embodiment of a patient interface device according to our new design; FIG. 9 is a rear perspective view of the patient interface device shown in FIG. 8; FIG. 10 is a front elevational view of the patient interface device shown in FIG. 8; FIG. 11 is a rear elevational view of the patient interface device shown in FIG. 8; FIG. 12 is a right side elevational view of the patient interface device shown in FIG. 8, the left side elevational view being similar thereto; FIG. 13 is a top plan view of the patient interface device shown in FIG. 8; and, FIG. 14 is a bottom plan view of the patient interface device shown in FIG. 8.

The portions drawn in broken lines are shown for illustrative purposes only and form no part of the claimed design.
